Primary Examiner — Lauren D McVey(74) Attorney, Agent, or Firm — Jose Cherson Weissbrot(57) CLAIM

The ornamental design for a photo album page, as shown and described.

DESCRIPTION

FIG. 1 is a first perspective view of a photo album page showing my new design;

FIG. 2 is a second perspective view thereof;

FIG. 3 is a front elevation view thereof;

FIG. 4 is a rear elevation view thereof; and,

FIG. 5 is an enlarged view of the encircled area in FIG. 1. The evenly spaced broken lines immediately adjacent to the claim depict the bounds of the claimed design, while all dot-dash broken lines depict the bounds of the enlarged views. The broken lines form no part of the claimed design.
